UNITED STATES PATENT OFFICE.

JAMES BARKER AND WILLIAM N. WINFIELD, OF DETROIT, MICHIGAN,
ASSIGNORS TO THE RICHMOND & BACKUS COMPANY, OF DETROIT,
MICHIGAN, A CORPORATION OF MICHIGAN.

LEDGER OR BINDER.

SPECIFICATION forming part of Letters Patent No. 777,932, dated December 20, 1904.

Application filed August 4, 1903. Serial No. 168,175.

To all whom it may concern:

Be it known that we, JAMES BARKER and WILLIAM N. WINFIELD, citizens of the United States, residing at Detroit, in the county of Wayne and State of Michigan, have invented 5 certain new and useful Improvements in Ledgers or Binders, of which the following is a specification, reference being had therein to the accompanying drawings.

10 The invention relates particularly to loose-leaf ledgers or binders wherein one of the covers or a clamping member is adapted to slidingly engage the binder-posts; and the invention consists in the novel and simple means 15 for locking the cover or the clamping member to the posts.

The invention further consists in the peculiar arrangement and combination of the various parts of the locking mechanism and in 20 other details of construction, as will be more fully hereinafter set forth.

In the drawings illustrating our invention, Figure 1 is a sectional perspective view of the ledger or binder. Fig. 2 is a view of the under side of a portion of one of the covers, showing the location of the locking means. Fig. 3 is a similar view, the locking mechanism being detached. Fig. 4 is a plan view of the locking mechanism. Fig. 5 is a similar 30 view showing the parts in their locked position; and Fig. 6 is a view in elevation, some of the parts being broken away, of the locking device.

In construction the ledger is composed of 35 the usual covers A and B, carrying, respectively, the clamping members C and D, which are connected to the covers by suitable flexible hinges E. Upon the clamping member D is arranged the binding-posts F, preferably two 40 in number, and of the sectional type. The upper clamping member C is apertured, as at a, to receive the posts and permit of a sliding engagement of the upper cover thereon.

b represents caps for the posts.

45 The under face of the clamping member C is recessed, as at c, to receive the locking mechanism, which consists, preferably, of a plate G, adapted to be rigidly secured by

screws or other like devices to the clamping member, locking-bars H and I, oppositely disposed upon the plate for sliding movement, and an operating member J for actuating the bars for the purpose of engaging the posts, and thereby locking the clamping member to which the plate is attached in its different positions of adjustment.

The locking-bars referred to are slotted, as at e, and are held in axial alinement on the plate G for sliding movement by suitable headed pins f. The outer ends of the bars 60 are curved and preferably sharpened, so as to engage and grip the post in the manner indicated in Fig. 5. The inner bar ends are provided with ears or lugs g, arranged in proximity to one another and adapted to receive 65 the operating member J, which in this instance is a screw-bolt. This bolt, as shown, has its outer end portion arranged within a bearing H' upon the plate G for endwise sliding movement, and its extreme end is made 70 hexagonal or square to receive a suitable key, by means of which the bolt is operated. The inwardly-projecting portion of the bolt is threaded to engage an internally-threaded aperture in the ear or lug upon the bar H, and 75 at its extremity the bolt is swiveled within the lug upon the bar I in the manner indicated in Figs. 4 and 5.

In operation when it is desired to lock the upper clamping member to the posts the 80 screw-bolt is rotated, by means of a key, in a direction to drive the locking members in opposite directions. Upon first rotating the bolt the bar H is moved toward and in contact with its binding-post, while upon continued rotation the locking-bar I is caused to grip its post, the bolt moving endwise through the bearing H', as indicated in Fig. 5.

By so arranging the locking members that they will be capable of moving independently 90 of each other it is always possible to have the bars properly grip the posts regardless of whether the latter are of the same diameter or of different diameters, and thus the upper cover or the clamping member will be effectively retained in its different positions. The

headed pins *f* serve as guides for the locking-
plates, preventing their turning during their
outward or inward movement and compelling
them to slide in a common plane. Further-
more, it will be observed that in case repairs
are necessary the entire locking mechanism
may be readily removed from the binder
cover or clamp in a simple manner by remov-
ing the screws or other securing devices which
hold the plate in place.

What we claim as our invention is—

1. In a loose-leaf ledger, the combination
with complementary clamping members, of
binding-posts carried by one of said members
and having sliding connections with the other
and means for locking the slidable member to
the posts, comprising a metallic plate secured
to the inner surface of said slidable member,
oppositely-disposed elongated thin flat lock-
ing-plates upon the metallic plate terminating
at their outer edges in sharpened curved por-
tions arranged to grip the inner sides of the
posts, and a rotary member mounted for end-
wise movement and having swivel and thread-
ed connections respectively with the locking-
plates.

2. In a loose-leaf ledger, the combination
with a clamping member, of binding - posts
thereon, a complementary member slidable on
the posts, a metallic plate secured to the inner
face of the slidable member, oppositely-dis-
posed slidable locking-bars upon the plate
having curved sharpened outer edges engag-
ing the posts, and upwardly-extending ears at
their inner ends disposed at right angles
thereto, pins on the plate engaging guideways
on the bars, and a rotatable member mounted
for endwise movement and having swivel and
threaded connections respectively with the
ears of the locking-bars.

3. In a loose-leaf ledger, the combination
with a clamping member, of binding - posts
thereon, a complementary member slidable on
the posts, a metallic plate secured upon the
under face of the slidable member, oppo-
sitely-disposed slidable locking-bars upon the

plate intermediate the posts, guides for said
bars compelling their movement in a common
plane, an ear or lug projecting at substantially
right angles from the adjoining end of each 50
locking-bar, a stationary bearing on the plate
near one end thereof, and a screw - bolt ar-
ranged within the bearing for endwise move-
ment and having swivel and threaded connec-
tions respectively with the lugs upon the lock- 55
ing-bars, substantially as and for the purpose
described.

4. In a loose-leaf ledger the combination
with complementary clamping members, of
binding-posts carried by one of said members 60
and having sliding connections with the other,
and means for locking the slidable member
to the post, comprising flat oppositely-dis-
posed slidable locking-plates, having curved
sharpened outer edges for engaging the inner 65
edges of the posts, guide members passing
through slotted portions of the plates, and a
rotary member mounted for endwise move-
ment and having swivel and threaded connec-
tions respectively with right-angled exten- 70
sions of the inner ends of said locking-plates.

5. In a loose-leaf ledger, the combination
with complementary clamping members, of
binding-posts carried by one of said members,
and having sliding connections with the other, 75
and means for locking the slidable member
to the post, comprising elongated oppositely-
disposed flat slidable locking-plates having
means at their outer ends for engaging the
posts, and upwardly-extended ears at their 80
inner ends, said ears being at substantially
right angles to the plates, and a rotary mem-
ber mounted for endwise movement and hav-
ing swivel and threaded connections respec-
tively with said ears on the locking-plates. 85

In testimony whereof we affix our signatures
in presence of two witnesses.

JAMES BARKER.
